troit, Mich.

Application August 12, 1935, Serial No. 35,732

7 Claims. (Cl. 200—149)

This application relates to switches.

The principal object of the present invention is to provide, in electrical switches, arc suppressing means of novel operation and construction. The arc suppressing means here shown is in the nature of a box-like structure or housing surrounding and carrying a movable switch contact and telescoping over a pair of stationary switch contacts adapted to be connected to each other through the movable contact, and functions to exhaust the air around the contacts and thus smother the arc in the exhausted air space within the box on the action of withdrawing the movable contact. In addition, the walls of the box support and 15 guide the movable contact as it moves between the stationary contacts of the switch, and also insulate the movable contact from the switch actuator or handle.

The box-like structure is preferably of a carbonaceous or fibrous insulating material so that if there arises, on arcing, any vaporization of the walls of the box-like structure, there will be formed carbon dioxide, and since this gas will not support combustion, such vaporization is no great 25 disadvantage.

The box is formed with a central partition dividing it into cells in each of which is received a stationary contact and the central partition carries the movable contact; thus, on switch 30 opening, any arc that occurs will be divided and relatively isolated in the cells by the central partition and such division of the arc and such isolation minimizes the disadvantages attendant upon arcing.

The box is formed to fit closely around the stationary contacts and may well be considered as a movable cylinder sliding on a stationary piston; the cylinder-piston action is such that arcing incident to switch opening creates a rapidly 35 expanding gas which tends to accelerate the separation of the cylinder from the piston or, in other words, tends to accelerate switch break.

The fibrous box parts slide along the stationary contacts and since these are of metal (copper preferred), no undue friction exists as might possibly be the case in the event the fibrous box parts were mounted to slide along fibrous mountings or the like of the stationary contacts. The coefficient of friction in the case of fiber-copper is 45 much less than that in the case of fiber-fiber.

Because of the long, close fit, bearing of the cell walls on the free ends of the stationary contacts in the cells, the stationary contacts serve as guides and mounts for the housing. Because 50 the box fits closely around the stationary con-

tacts, the cells thereof, when the switch is on, are substantially completely filled by the stationary contacts; thus, on movement of the box from the stationary contacts, the cell volumes are expanded to a tremendous extent thereby rarifying the cells considerably. 5

Still further advantages of the present invention will be best understood upon reference to the following detailed descriptive matter and to the appended drawings, whose

Figs. 1 and 2 show parts in circuit ruptured and circuit established position;

Figs. 3 and 4 are end views of the movable and stationary parts of the switch;

Fig. 5 shows a modification wherein the movable contact includes a part insertable between the stationary contacts and a part adapted to embrace the stationary contacts; 15

Figs. 6 and 7 show another modification;

Figs. 8 and 9 show a switch whose arrangement 20 of contacts differs from that of Figs. 1-7 inclusive.

Referring to Figs. 1-4 of the drawings it will be seen that the switch there shown includes a base 25 upon which are mounted stationary contacts 11 (of copper or the like) adapted to be connected to line and load respectively through conductors whose terminals are secured and connected by the connectors 12. For cooperation with and for bridging the gap between the stationary contacts there is provided a movable contact 14 in the form of a copper slug carried by a blade 15 of fibrous and carbonaceous insulation, the blade being part of a box-like structure comprising a plate 30 16, an actuator handle 17, exterior portions 18 spaced from the blade 15 to define cells 19 receiving the fingers of the stationary contacts, and edge portions 20 which connect the blade 15 and the exterior portions 18 at the edges of the same 35 to close the cells 19 at their edges. 40

It is observed that reciprocation of the movable parts establishes or ruptures the circuit and that the extreme limits of movement of the movable parts with respect to the stationary parts 45 are such that the fingers of the stationary contacts are at all times closely surrounded by portions of the box-like structure. Withdrawal of the blade and the box-like structure partially exhausts the air within the box-like structure and 50 thus suppresses the arc formed by withdrawal of contact 14 from between the stationary contacts. It is also observed that portions of the box-like structure mount the movable contact 14 and 55 guide the latter in its switching movement, and

also physically connect it to but electrically separate it from the actuator handle 17.

It is also observed that any arc that occurs on switch withdrawal will be divided and the divisions isolated by the cell forming partition or blade 15.

The box, with its blade, is so dimensioned that the cells 19 closely fit the fingers of the stationary contacts; accordingly, gases generated by arcing 10 incident to switch withdrawal will tend to separate the box (cylinder) from the fingers (piston) and thus will tend to accelerate switch withdrawal.

Though the fit between the fibrous walls of 15 cells 19 and the fingers is a close fit, no undue friction will be created to impede switching action, for the coefficient of friction between fiber and copper (or the like) is not excessive.

For limiting withdrawal movement of the 20 movable parts from the stationary parts and for supplementing the stationary contacts in their function of supporting and guiding the movable parts in their switching movement, there are 25 provided guides 21 received within notches 22 of the plate 16 and formed with restraining lugs 23.

If desired, the box-like structure may be made 30 of laminae, rather than monolithic, substantially as shown in Fig. 5, and if desired an auxiliary contact 24 may be provided to embrace the fingers 35 of the stationary contacts and electrically connect them in a path parallel to the path through the slug 14. As shown, the tips of the contact 24 may project beyond the edges of the slug 14, in the manner of arc-tips, so that these tips engage the stationary contacts before and leave the same after the slug 14 has engaged or left the stationary contacts.

Figs. 6 and 7 show how the portions 18 may be 35 of sheet fiber, formed or shaped as shown.

40 Figs. 8 and 9 show how the stationary contacts 29 may be staggered to increase the gap between them, in which case the complementarily formed movable contact parts will include conduction portions 30—30a adapted to engage opposite sides 45 of the stationary contacts, with the movable contacts being carried by an insulation block formed to provide a portion 31 which separates the stationary contacts. In such case, the contact 30 may be made longer than the contact 30a 50 so that it will make before and break after the contact 30a does, in order to approximate the arc-tip function performed by the contacts 24 of Fig. 5.

What is claimed is:

55 1. In a switch, the combination of two rigidly mounted, inflexible, sturdy, relatively insulated adjacent parallel stationary contacts having free ends, one of the contacts being permanently connected to an energized line so as to be normally live, a housing of insulation comprising two adjacent parallel insulation cells disposed over and capping the free ends of the stationary contacts, the housing thus being mounted by the stationary contacts for reciprocation along them, each cell 60 containing a contact for making with a stationary contact, means within the housing for interconnecting the cell contacts so as to connect the stationary contacts to each other when the cell contacts make with the stationary contacts, the walls 65 of the cells, all the way from the cell contacts to the free ends of the adjacent stationary contacts, measured when the cell contacts do not make with and are remote from the stationary contacts, being formed to fit and surround closely 70 the stationary contacts so that the stationary

contacts will provide a long, close fitting, and accurate mounting and guide for the housing in its reciprocation, and means outside of and connected to the housing for causing its reciprocation and being insulated from the cell contacts 5 and the stationary contacts by the housing itself, the cell volume, when the switch is closed, being substantially completely filled by the stationary contacts, means for preventing complete withdrawal of the movable housing from the stationary contacts and designed to permit sufficient withdrawal thereof to enable the movable contacts to leave the stationary contacts and to enable the free space in the cells to be expanded to a considerable extent for rarification thereof, 15 and to insure the stationary contacts closing the cells at all times, the fit between the stationary contacts and the cell walls being so close and their relative proportions being so similar that during cell withdrawal no substantial infiltration of air 20 into the cell arises to minimize the rarification that occurs on such withdrawal.

2. In a switch, the combination of two rigidly mounted, inflexible, sturdy, relatively insulated adjacent parallel stationary contacts having free 25 ends, one of the contacts being permanently connected to an energized line so as to be normally live, a housing of insulation comprising two adjacent parallel insulation cells disposed over and capping the free ends of the stationary contacts, 30 the housing thus being mounted by the stationary contacts for reciprocation along them, each cell containing a contact for making with a stationary contact, means within the housing for interconnecting the cell contacts so as to connect the 35 stationary contacts to each other when the cell contacts make with the stationary contacts, the walls of the cells, all the way from the cell contacts to the free ends of the adjacent stationary contacts, measured when the cell contacts do 40 not make with and are remote from the stationary contacts, being formed to fit and surround closely the stationary contacts so that the stationary contacts will provide a long, close fitting, and accurate mounting and guide for the housing 45 in its reciprocation, and means outside of and connected to the housing for causing its reciprocation and being insulated from the cell contacts and the stationary contacts by the housing itself, the cell volume, when the switch is closed, 50 being substantially completely filled by the stationary contacts, means for preventing complete withdrawal of the movable housing from the stationary contacts and designed to permit sufficient withdrawal thereof to enable the movable contacts 55 to leave the stationary contacts and to enable the free space in the cells to be expanded to a considerable extent for rarification thereof, and to insure the stationary contacts closing the cells at all times, the fit between the stationary contacts and the cell walls being so close and their relative proportions being so similar that during cell withdrawal no substantial infiltration of air 60 into the cell arises to minimize the rarification that occurs on such withdrawal, the cells being so constructed as to be sealed everywhere except for the openings through which pass the stationary contacts, the fit between the cell walls and the stationary contacts in such openings being so tight that the stationary contacts 65 seal the cells, whereby withdrawal of the housing from the stationary contacts for causing separation of the cell contacts from the stationary contacts is accompanied by a rarification of 70 the atmospheres within the cells.

3. The combination of two rigidly mounted, inflexible, sturdy, relatively insulated adjacent parallel stationary contacts having free ends, one of the contacts being permanently connected to an energized line so as to be normally live, a housing of insulation comprising two adjacent parallel insulation cells disposed over and capping the free ends of the stationary contacts and having a common separating wall, the housing thus being mounted by the stationary contacts for reciprocation along them, each cell containing a contact for making with a stationary contact, means within the common separating wall of the housing for interconnecting the cell contacts so as to connect the stationary contacts to each other when the cell contacts make with the stationary contacts, the walls of the cells, all the way from the cell contacts to the free ends of the adjacent stationary contacts, measured when the cell contacts do not make with and are remote from the stationary contacts, being formed to fit and surround closely the stationary contacts so that the stationary contacts will provide a long, close fitting, and accurate mounting and guide for the housing in its reciprocation, and means outside of and connected to the housing for causing its reciprocation and being insulated from the cell contacts and the stationary contacts by the housing itself, the cell volume, when the switch is closed, being substantially completely filled by the stationary contacts, the fit between the stationary contacts and the cell walls being so close and their relative proportions being so similar that during cell withdrawal no substantial infiltration of air into the cell arises to minimize the rarification that occurs on such withdrawal.
4. The combination of two rigidly mounted, inflexible, sturdy, relatively insulated adjacent parallel stationary contacts having free ends, one of the contacts being permanently connected to an energized line so as to be normally live, a housing of insulation comprising two adjacent parallel insulation cells disposed over and capping the free ends of the stationary contacts and having a common separating wall, the housing thus being mounted by the stationary contacts for reciprocation along them, each cell containing a contact for making with a stationary contact, means within the common separating wall of the housing for interconnecting the cell contacts so as to connect the stationary contacts to each other when the cell contacts make with the stationary contacts, the walls of the cells, all the way from the cell contacts to the free ends of the adjacent stationary contacts, measured when the cell contacts do not make with and are remote from the stationary contacts, being formed to fit and surround closely the stationary contacts so that the stationary contacts will provide a long, close fitting, and accurate mounting and guide for the housing in its reciprocation, and means outside of and connected to the housing for causing its reciprocation and being insulated from the cell contacts and the stationary contacts by the housing itself, the cell volume, when the switch is closed, being substantially completely filled by the stationary contacts, the fit between the stationary contacts and the cell walls being so close and their relative proportions being so similar that during cell withdrawal no substantial infiltration of air into the cell arises to minimize the rarification that occurs on such withdrawal, the cells being so constructed as to be sealed everywhere except for the

openings through which pass the stationary contacts, the fit between the cell walls and the stationary contacts in such openings being so tight that the stationary contacts seal the cells, whereby withdrawal of the housing from the stationary contacts for causing separation of the cell contacts from the stationary contacts is accompanied by a rarification of the atmosphere within the cells.

5. In a switch, a base, two stationary contacts mounted thereon and permanently connected to circuit lines, with one of them being permanently live, both having adjacent parallel free ends, a movable contact for engaging the free ends of the stationary contacts and thus bridging them, means manipulable for reciprocating said movable contact towards and away from the stationary contacts, and a single means for operatively connecting the movable contact to the manipulable means whereby movement of the latter will cause movement of the former and for supporting and guiding the movable contact in its movement and for constantly shielding and enclosing the movable contact and for constantly shielding and enclosing the free ends of the stationary contacts and for providing an enclosing housing around the contacts during their separation comprising a unitary housing structure having two hollow solid walled cells of insulating material in the interior of each of which is a part of the movable contact, each hollow cell being sealed throughout except at one open end in which is permanently disposed the free end of one of the stationary contacts, the transverse cross sectional area of each cell interior, measured all the way from end to end of the cell, being very closely dimensioned to that of the free end of the stationary contact therewithin so that the latter provides a bearing and guide for the cell in its movement, the manipulable means being outside of and connected to the housing, and means for limiting movement of the movable contact away from the stationary contacts to an extent insufficient to permit the cells ever to leave the stationary contacts and thus expose the latter or uncouple the cells and the stationary contacts, the free ends of the stationary contacts being relatively close to each other, sufficiently to provide a magnetic path between them, and the cells of the housing having a common separating wall which is proportioned to slide between the free ends of the stationary contacts and in which common separating wall is disposed the movable contact.
6. In a switch, a base, two stationary contacts mounted thereon and permanently connected to circuit lines, with one of them being permanently live, both having adjacent parallel free ends, a movable contact for engaging the free ends of the stationary contacts and thus bridging them, means manipulable for reciprocating said movable contact towards and away from the stationary contacts, and a single means for operatively connecting the movable contact to the manipulable means whereby movement of the latter will cause movement of the former and for supporting and guiding the movable contact in its movement and for constantly shielding and enclosing the movable contact and for constantly shielding and enclosing the free ends of the stationary contacts and for providing an enclosing housing around the contacts during their separation comprising a unitary housing structure having two hollow solid walled cells of insulating material in the interior of each of which is a part of the movable contact.

- contact, each hollow cell being sealed throughout except at one open end in which is permanently disposed the free end of one of the stationary contacts, the transverse cross sectional area of each cell interior, measured all the way from end to end of the cell, being very closely dimensioned to that of the free end of the stationary contact therewithin so that the latter provides a bearing and guide for the cell in its movement, 5 the manipulable means being outside of and connected to the housing, and means for limiting movement of the movable contact away from the stationary contacts to an extent insufficient to permit the cells ever to leave the stationary contacts 10 and thus expose the latter or uncouple the cells and the stationary contacts, each cell volume being so dimensioned to that of that part of the stationary contact therewithin when the switch is closed that each cell interior is substantially 15 completely filled by a stationary contact whereby movement of the housing away from the base causes a tremendous increase in the free volume of each cell interior, the free ends of the stationary contacts being relatively close to each 20 other, sufficiently to provide a magnetic path between them, and the cells of the housing having a common separating wall which is proportioned to slide between the free ends of the stationary contacts and in which common separating wall 25 is disposed the movable contact.
7. In a switch, the combination of a prong, an insulation cell telescopically disposed over and capping the free end of the prong, the cell and prong being mounted for relative telescopic reciprocation, the cell containing a contact for making 30

with the prong and being closed throughout except for one open end adapted to be closed by the prong, the wall of the cell, all the way from the cell contact to the free end of the prong, measured when the cell contact does not make with and is most remote from the prong, being formed to fit and surround closely the prong so that the prong and cell will provide a long, close fitting and accurate mounting and guide for the prong and cell in their relative reciprocation, 10 the cell volume, when the switch is closed, being substantially completely filled by the prong, means for preventing complete withdrawal of the cell and prong relatively and designed to permit relative withdrawal to an extent sufficient to 15 permit the cell contact to be separated from the prong and to enable the free space in the cell to be expanded to a considerable extent for rarification thereof and to insure the prong closing the cell at all times, the fit between the prong and the cell 20 wall being so close and their relative proportions being so similar that during cell withdrawal no substantial infiltration of air into the cell arises to minimize the rarification that occurs on such withdrawal, the cell being so constructed as to 25 be sealed everywhere except for the opening through which passes the prong, the fit between the cell wall and the prong in such opening being so tight that the prong seals the cell, whereby withdrawal of the cell from the prong for causing 30 separation of the cell contact from the prong is accompanied by a rarification of the atmosphere within the cell.
